QUICK DISCONNECT KEY HOLDER

Paul T. Poutinen, Manhasset, N. Y.

Application April 4, 1950, Serial No. 153,852

2 Claims. (Cl. 70—457)

1

This invention relates to a holder for keys from which a chain with a bunch of keys thereon may be quickly disconnected or separated from the holder for use.

Bunches of keys are usually carried in the pockets or pocket books or hand bags on chains thus making it necessary to make the chain small and the fastening latches correspondingly small with the result that it is difficult to manipulate the fastening latches making it troublesome and time wasting to remove the keys.

It is desirable to carry all keys on a single holder for convenience and to save space and it is also often found desirable to keep the keys for the house, for example, in a bunch separate from the bunch of keys for the automobile and garage, for example, so that either bunch may be removed from the holder and handed to a person for use.

It is a prime object of the present invention to provide a device for holding chains of keys at both of its ends, with at least one chain with the keys thereon being quickly separated or disconnected from the device for use.

Another object of the invention is to provide a key holder with means for quickly mounting and demounting a key chain therefrom.

Still another object is to provide a key holder with novel means at one end for locking a key chain thereto.

Yet another object is to provide a holder of this kind that is simple and compact and convenient for carrying on the person.

Other objects and advantages of the invention will be apparent from the description thereof to follow taken in connection with the accompanying drawings in which—

Fig. 1 is a plan view of a key holder embodying one form of my invention, showing key chains supported at both ends.

Fig. 2 is a detail plan view showing a key chain supporting unit.

Fig. 3 is a detail fragmentary side view of the unit of Fig. 2.

Fig. 4 is an end view thereof looking from the left hand end.

Fig. 5 is an end view thereof looking from the right hand end.

Fig. 6 is a sectional view of the unit of Fig. 2 showing the stem in open position.

Fig. 7 is a vertical sectional view of a modified form of key chain supporting unit, showing the stem in chain supporting position.

Fig. 8 is a similar view showing the stem in open position.

2

Fig. 9 is a sectional view taken on the plane of the line 9—9 of Fig. 7.

Fig. 10 is a plan view partly in section showing another modified form of key holder embodying my invention.

Fig. 11 is a side view of another modification.

Referring to the drawing, the form of key holder shown in Figs. 1 to 6 inclusive comprises an elongated cylindrical body 10 of metal, preferably tubular. At one end, the body is closed and has an opening 11 extending therethrough for receiving an endless chain 12 for holding a bunch of keys 13 thereon. The chain is provided with the usual fastening latch 14 for fastening and unfastening its ends.

The opposite end of the body is closed by a key holding unit comprising a tubular casing 15 fitted therein.

The casing has an extension 16 of reduced diameter, the bottom inner end of said

extension forming an inner shoulder 17. Slidable through the extension 16 and the casing 15

is a stem or plunger 18. The stem is formed with an internally screw threaded socket portion

19 axially of its inner end for receiving the shank

20 of a screw 20. Encircling the inner end portion

of the stem 18 is a helical spring 21. One end

of the spring seats on the head 22 of the screw

and its other end impinges against the shoulder

17 of the casing whereby the stem 18 is urged

inwardly of the casing. When the stem is in its

innermost position, the head of the screw closes

the open inner end of the casing. The screw

serves to adjust the pressure of the spring.

The outer end of the stem 18 projects beyond

the extension 16 of the casing and is formed

with a head 23 which is notched as indicated at

24 forming a nose portion 25, or hook portion.

The tip of the nose or hook portion is adapted

to engage the upper edge of the extension 16

and with said extension forms an enclosure 26

as shown in Figure 2 for receiving and locking an

endless chain 27 carrying keys 28.

The stem is guided in its movement through

the extension and casing by the head 22 of the

screw 20 and by a pin 29 carried by the stem

and riding in an elongated slot 30 formed in the

stem 18 and intersecting its outer edge.

When it is desired to separate or disconnect

the chain 27 with its keys 28 from the holder, it

is merely necessary to pull manually on the chain

in the direction of the axis of the casing 15

against the action of spring 21 whereby the stem

or plunger will be moved outwardly of the exten-

sion 16 of the casing carrying its nose or hook

portion 25 away from the upper or outer edge

of the extension 16 and carrying its pin 29 beyond and free of the slot 30 and of the outer edge of the extension. The stem is then given a partial turn to bring its pin 29 to one side of the slot 30. When the manual pulling pressure is released, the stem will be forced inwardly by the action of the spring 21 on the head of the screw 20 until its pin 29 engages and abuts against the outer edge of the extension 16 thereby holding the stem in its outward position as shown in Fig. 6. The enclosure 26 will thus be opened and the chain 27 with its keys may be quickly separated and disconnected from the hook or nose portion of the stem for use.

To replace the chain 27 with its keys on the 15 holder, it is placed under the hook or nose portion 25 of the stem and the stem given a partial turn back until its pin 29 registers with the slot 30 to permit the spring 21 to pull or force the stem inwardly of the casing and extension 20 and bring its nose or hook portion into engagement with the outer edge of the extension to lock the chain on the holder again.

The chain 12 with its keys 13 may be separated from the holder by unfastening its latching member 14 as is usual.

In the modified form of chain holding unit shown in Figs. 7 to 9, inclusive, the stem 31 is formed with an annular groove 32 therearound and with an elongated groove 33 therealong. The 30 extension 34 of the casing 35 is provided with an inwardly extending lug 36 adapted to slide in the groove 33 when the stem is pulled outwardly or moved inwardly of the extension. In order to hold the stem in outermost position or open 35 position, the stem is given a partial turn until its slot 33 is moved laterally of the lug 36 whereupon the lug engages the shoulder 37 on the stem formed by the annular groove 32 and prevents inward movement of the stem. To retract the stem, it is turned back until the slot or groove 33 registers with the lug 36 whereupon the spring 38 will force the stem inwardly.

In Fig. 10, the chain supporting unit of Fig. 2 is shown slidably mounted in and closing one 45 end of a casing 39 of a flashlight. The casing 15 of the unit is slidably positioned and is provided with a central protuberance 48 which is adapted to engage the central contact 41 of the battery 42 for closing the circuit through the lamp (not shown) in the flashlight, when the casing 45 is manually moved inwardly. The other end of the flashlight casing supports an endless chain 43 or the like with its keys 44 in the usual manner.

In Fig. 11, a flashlight 45 is shown having one end supporting and closed by a chain supporting unit as in Fig. 10, but in this form of unit the outer end of the head 46 of the stem 18 is enlarged or elongated and is provided with an opening 47 for receiving an endless chain 48 or the like with keys 49. No key chain is provided at the opposite end of the flashlight 45.

It will be understood that instead of an endless chain for holding the keys, any suitable type of chain or other flexible fastening member or a metal ring may be used for holding the keys.

I claim:

1. A quick detachable key holder comprising an elongated tubular body closed at one end and having a key chain supporting unit closing the other end of the body including a tubular casing and a spring controlled stem slidably in said casing, said stem having a notched portion adapted to coact with said tubular casing for detachably receiving a key chain and means for holding the stem in moved position including a pin carried by the stem adapted to abut against the end of the tubular casing.

2. A quick detachable key holder comprising an elongated tubular body closed at one end and having a key chain supporting unit closing the other end of the body including a tubular casing and a spring controlled stem slidably in said casing, said stem having a notched portion adapted to coact with said tubular casing for detachably receiving a key chain and means for holding the stem in moved position including a slot and stud connection between the stem and tubular casing.

PAUL T. POUTINEN.
